UNITED STATES PATENT OFFICE.

GEORGE F. PARKER, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A PLATE OR ANALOGOUS ARTICLE.

Application filed February 17, 1923. Serial No. 5,191. Term of patent 7 years.

To all whom it may concern:

Be it known that I, GEORGE F. PARKER, a citizen of the United States, residing at Newburyport, in the county of Essex and State of Massachusetts, have invented a new, original, and ornamental Design for a Plate or Analogous Article, of which the following is a specification, reference being had to the accompanying drawing, forming a part thereof.

The figure of the drawing is a plan view of a plate showing my new design.

The dominant feature of the design comprises an ornamental border decoration, a section only of which is shown in the accompanying drawing, it being understood from the delineation that the novel border motif is repeated throughout the periphery of the plate.

I claim:

The ornamental design for a plate or analogous article, substantially as shown and described.

GEORGE F. PARKER.
